(57) **CLAIM**

The ornamental design for a valve, as shown and described.

DESCRIPTION

FIG. 1 is a perspective view of a valve, showing my new design;

FIG. 2 is a front elevational view of the valve shown in FIG. 1;

FIG. 3 is a rear elevational view of the valve shown in FIG. 1; FIG. 4 is a left-side elevational view of the valve shown in FIG. 1;

FIG. 5 is a right-side elevational view of the valve shown in FIG. 1;

FIG. 6 is a top plan view of the valve shown in FIG. 1; and, FIG. 7 is a bottom plan view of the valve shown in FIG. 1. The broken line showing of houses is included for the purpose of illustrating portions of the valve and forms no part of the claimed design.
